DESCRIPTION

U.S. PATENT DOCUMENTS

FIG. 1 is a perspective view of the top, front and left side of an elastic body for electronic weighing scale showing our new design;

4,799,561 1/1989 Komoto .
4,813,505 3/1989 Sodler et al. .
5,315,073 5/1994 Ast et al. .

FIG. 2 is a left side elevational view thereof;

FIG. 3 is a right side elevational view thereof;

FIG. 4 is a top plan view thereof;

FIG. 5 is a front elevational view, the rear elevational view being a mirror image thereof; and,

FIG. 6 is a bottom plan view thereof.
